Inventor:-

John F. Cordes
By his Atty. *W. H. Row*

UNITED STATES PATENT OFFICE.

JOHN F. CORDES, OF CHICAGO, ILLINOIS.

TRANSFER-FRAME FOR LETTER-FILES AND BINDERS.

SPECIFICATION forming part of Letters Patent No. 703,767, dated July 1, 1902.

Application filed February 2, 1901. Serial No. 45,750. (No model.)

To all whom it may concern:

Be it known that I, JOHN F. CORDES, a citizen of the United States, residing at Chicago, in the county of Cook and State of Illinois, ⁵ have invented certain new and useful Improvements in Transfer-Frames for Letter-Files, of which the following is a specification.

My invention relates to a transfer arch frame or carrier to be used with letter-files ¹⁰ and loose-leaf binders, order-blanks, and receipt-holders of the class known as "post-bindlers;" and the object of my invention is to provide an improved simple device which may be adjusted to various binders having ¹⁵ posts at different distances apart and which when not in use may be folded up into a compact form.

My invention consists in two base-bars hinged together, each having an arch-post ²⁰ swiveled to the swinging ends thereof, the arched ends of the said posts being provided with cups or suitable end fittings to connect with the upper ends of the impaling-posts of the binder, the arch-posts being thus adapted ²⁵ to move toward and from each other and the arched upper ends thereof to be held away from the hinged bars and parallel to each other, when in use, and to be turned backwardly to overhang the said hinged bars when ³⁰ the frame is folded up into a compact form.

In the accompanying drawings, which illustrate my invention, Figure 1 is a perspective view of my improved transfer-frame applied to a post-binder. Fig. 2 is a plan view of the ³⁵ transfer-frame upon an enlarged scale, showing by dot-lines the frame in a second position; and Fig. 3, a perspective view of the transfer-frame folded up.

The base-bars A A are hinged together at ⁴⁰ a and their opposite ends are bored and receive arch-posts B B, pivoted thereto at b, the said arch-posts being thus adapted to be swung either away from the base-bars in parallel lines as shown in Figs. 1 and 2, to engage ⁴⁵ with the binder-posts D D of a post-binder E, and also to be moved toward and away from each other in parallel lines as shown in Fig. 2, thus to adapt the transfer-frame to various binders having posts at unequal distances

from each other, the dot-lines in Fig. 2 representing the position of the frame when adapted to posts that are nearer to each other than that shown by full lines in the same figure. ⁵⁰

The pivotal connection of the arch-posts to the swinging ends of the hinged base-bars ⁵⁵ will allow the arches of the arch-posts to be turned back over the said base-bars when the latter are folded together, as shown in Fig. 3, thus allowing the frame to be doubled up into a compact form and hung or put up away ⁶⁰ when not in use. The transfer-frame may be thus used for any number of binders of different sizes, and the parts being all securely joined together and moving freely on their connections are not liable to be lost, ⁶⁵ strained, or broken.

The transfer-frame, as with other non-adjustable devices for the same purposes, may be used either for temporarily turning over or transferring the superimposed leaves from ⁷⁰ the post-binder to the transfer-frame to get access or to remove a certain letter from the post-binder or to remove all of the letters or sheets therefrom and serve as a carrier to hold the said sheets and enable them to be ⁷⁵ transferred to a permanent binder when required.

The arch-posts may be secured into the ends of the hinged base-bars and removed therefrom when the device is to be packed ⁸⁰ away; but this construction is considered defective.

In large binders three or four posts are sometimes employed, and it is evident that a double set of hinged base-bars for each additional post required may be employed. ⁸⁵

I claim as my invention and desire to secure by Letters Patent—

1. The combination with a jointed base, of posts adjustably secured thereon and socketed ends on said posts. ⁹⁰

2. In a device of the class described, the combination with hinged base-bars of a post adjustably secured on each, curved ends on said posts and means for engaging the same ⁹⁵ on the posts of a loose-leaf binder.

3. The combination with a plurality of curved posts, of means on each for engaging

the posts of a loose-leaf binder and jointed base-sections adjustably engaging said posts and adapted to permit the same to be adjusted to varying distances apart.

5. A transfer-frame comprising a plurality of articulated base-bars, posts adjustably and rotatably supported on each, the free end of

each post being curved downwardly and provided at its extremity with a socket adapted to engage over a post of a loose-leaf binder.

JOHN F. CORDES.
